UNITED STATES PATENT OFFICE.

NILS E. NORSTROM, OF CHICAGO, ILLINOIS, ASSIGNOR TO N. E. NORSTROM ELECTRIC MANUFACTURING COMPANY, OF CHICAGO, ILLINOIS, A CORPORATION OF ILLINOIS.

ELECTROMAGNET.

Application filed August 23, 1920. Serial No. 405,511.

To all whom it may concern:

Be it known that I, NILS E. NORSTROM, citizen of the United States of America, and a resident of Chicago, county of Cook, and State of Illinois, have invented certain new and useful Improvements in Electromagnets, of which the following is a specification.

My invention relates to electro-magnets and is of particular service in relation to electro-magnets that are used in the construction of vibratory apparatus which is employed to agitate or vibrate parts of the human body although the magnet of my invention is not to be limited to this utility. A vibrating mechanism made in accordance with my invention has the agitating contact element thereof provided upon an extending from the magnet armature in the direction in which the armature is magnetically attracted, the magnet being responsive to wave form current so that when the agitating element is pressed against the body to put the armature in a retracted position the armature will vibrate or chatter responsive to the fluctuating magnetism due to the wave form current in its effort to assume attracted position thereby to produce the desired vibration of the agitating element.

The magnet of my invention includes an armature formed of assembled relatively movable laminae so that various portions of the armature may be placed in different positions with respect to the armature winding or core. The laminae forming the armature are preferably swingingly mounted, the laminae then being parallel with the plane of armature movement. For certain purposes such a magnet is equipped with an armature adjusting element successively engaging the armature laminae to place them at varying distances from the magnet core.

In the preferred embodiment of the invention the normal range of operation of this adjusting element is such that some of the laminae do not leave the core thereby maintaining a portion of the magnetic circuit normally closed through iron. By forming the armature of laminae it may more easily be moved away from the magnet core since the laminae may be moved one by one in succession requiring minimum effort to separate it from the magnet core. By giving to the armature a normal range of move-

ment which would permit some of the armature laminae constantly to remain in engagement with the poles of the magnet core the magnet winding would remain cool, the occasional movement of the entire armature being permitted when, for example, extraordinary agitation of the agitating element is required, but as the movement of the entire armature away from the core is not apt to occur frequently the magnet winding will not have opportunity to become materially heated. This is a result which is important in the construction of vibrating apparatus and is useful in other connections.

I will explain my invention more fully by reference to the accompanying drawing showing the preferred embodiment thereof and in which Fig. 1 illustrates the magnet of my invention included in the formation of vibrating mechanism that is made in accordance with my invention; Fig. 2 is a sectional view on line 2-2 of Fig. 1; Fig. 3 is a sectional view on line 3-3 of Fig. 1; Fig. 4 illustrates on a larger scale the forward end of the armature when this armature is fully resting at its forward end upon the magnet core; and Fig. 5 is a similar view illustrating the changed position of the armature adjusting element that successively engages the armature laminae.

The electro-magnet illustrated is one which is adapted to respond to alternating or wave form current. This magnet includes a core 1 formed of E-shaped laminae. The magnet winding 2 is placed around the middle branch of the core, the core defining a double magnet circuit. The core illustrated is virtually a double U-core, the middle branch of the core being common to the two U's. I do not, however, wish to be limited to any particular shape of the magnet core. The laminae of the magnet core are desirably clamped together by a rectangular frame 3 surrounding the base of the core, and a rectangular frame 4 surrounding the polar portions of the core, these frames being assembled with the magnet casing 5. A pivot rod 6 is supported by two opposite sides of the frame 4 above one of the outer magnet poles and transversely of the laminae forming the magnet core. The laminae 7 composing the armature are loosely mounted upon this rod, which is so positioned that the laminae of the armature

will remain in contact with the outer polar end of the core over which said rod 6 is disposed. The adjacent lower corner of each lamina is rounded so that as such lamina is turned it will maintain a rolling contact with the core. The armature laminae and the core laminae are parallel with the plane of armature movement. The forward ends of the laminae are adapted to rest upon the other outside polar end of the core, these forward ends of the laminae being provided with aligned holes 7¹. A rod 8 projects through these holes in one-half of the armature laminae while another rod 9 projects through these holes in the remaining laminae. When the forward ends of the armature laminae are rested upon the core 1, the openings 7¹ in the laminae that surround the rod 8 and in the laminae that surround the rod 9 are, as groups, converged inwardly or toward each other. The rods 8 and 9 are in the same plane and approximately aligned. These rods are desirably reduced at their adjacent ends where they have such engagement with a few of the laminae at the middle portion of the armature structure as to be adapted to move these laminae simultaneously. In other parts of the armature structure, however, owing to the inclination of the remaining hole 7¹, the rods 8 and 9 are adapted for successive engagement with the armature laminae to cause them to move successively toward or away from the magnet core according to the direction of movement of the armature. The number of laminae that are separated from the core depends upon the extent to which the inner ends of the rods 8 and 9 are moved away from the core, the normal range of such movement being such that a plurality of laminae 7 at each side of the armature will remain in magnet circuit closing engagement with the three poles of the magnet core so that the magnetic flux at the sides of the magnet will encounter minimum reluctance. However, the inner ends of the rods 8 and 9 may be so far raised as to lift the entire armature at its forward end from the core. The outer ends of the rods 8 and 9 engage sides of the frame 4 to maintain them in assembly with the laminae 7, the maximum movement of the armature being such that these rods will not be brought above said frame. These rods 8 and 9 thus constitute adjusting elements that successively engage the armature laminae, each of these adjusting elements being operable by a lamina or a plurality of laminae.

In the embodiment of the invention illustrated the rods 8 and 9 are included in an armature adjusting or retracting element which also embraces a stem 10 pivotally connected with the extensions 11 of those laminae which surround the adjacent reduced ends of the rods 8 and 9. This stem extends from the magnet armature in the direction in which the armature is magnetically attracted so that by pushing upon the stem the armature will be given retracting movement or pressure. The stem 10 carries the agitating contact element 12 which may have a variety of shapes and purposes, only one shape being illustrated in the drawing. The stem 10 passes through the casing 5 which houses the magnet and its armature and the greater portion of the stem 10. The casing also supports the hollow handle structure 14 through which the conducting wires 15 are extended into connection with the magnet winding.

Assuming that the magnet is connected with a source of alternating current, it is apparent that by pressing the agitating element 12 against the body the armature may be given a retracting movement against the tractive force of the magnet. If this pressure is comparatively slight only those magnet laminae 7 which are pivotally connected with the stem 10 will be lifted against the attractive force of the magnet, the balance of the laminae continuing to maintain the magnet circuit to avoid heating of the winding. When the retracting pressure upon the stem 10 is increased additional laminae 7 are moved away from the magnet core. The amount of attractive force which has to be overcome by the armature retracting pressure upon the stem 10 increases with the separation of the laminae 7 from the magnet core. If the magnet is in an alternating or wave form current circuit the armature will be subject to vibration due to the alternations or waves in the current and the corresponding fluctuating flux in the core of the magnet. By holding the armature in a given position through the medium of the stem 10 a vibration of the agitator 12 will result which corresponds to the tractive effort then exerted by the magnet upon its armature and the degree of which may be varied as stated.

It is quite apparent that the device of my invention is operative with only one rod 9, though I prefer the symmetrical arrangement afforded by the rods 8 and 9 for the sake of appearance and some minor advantages in the mechanism. It is also apparent that the armature described is a flexible one in that the surface of the armature when in retracted position is a warped surface as distinguished from a curved surface. In operation, the amount of this warping is a continually changing thing. As illustrated, it begins at the front central portion. If only one rod 9 is used, it will begin at a front corner. In either case, the rear contact under rod 6 is in a plane. While the magnet is shown included in the formation of a vibrating device it is not to be limited to this use.

What I claim is:

1. An electro-magnet provided with a swinging armature formed of assembled relatively movable laminæ which are substantially parallel with the plane of armature movement, in combination with an armature adjusting element operable by a lamina of the armature and adapted to successively engage the armature laminæ.
- 10 2. An electro-magnet provided with a swinging armature formed of assembled relatively movable laminæ which are substantially parallel with the plane of armature movement, the magnet having a core with one end in contact with the armature where mounted to swing and its other end engageable by said armature and means operable thru one lamina for retracting the armature by moving the laminæ with respect to each other.
- 15 3. An electro-magnet provided with an armature formed of assembled relatively
- 20 movable laminæ, in combination with an armature adjusting element adapted to successively engage the armature laminæ, said adjusting element having one portion adapted to engage and actuate a plurality of said laminæ simultaneously.
- 25 4. An electro-magnet provided with an armature formed of assembled relatively movable laminæ which are substantially parallel with the plane of armature movement, in combination with an armature adjusting element operable by a lamina of the armature and adapted to successively engage the armature laminæ.
- 30 5. The combination with an electro-magnet having a core, and an armature composed of laminæ each one of which has one end in rolling contact with one end of the core, of means for moving the other ends of the laminæ successively to and from contact with the other end of the core.
